UNITED STATES PATENT OFFICE.

MATTHEW T. MCKENNA, OF SAN FRANCISCO, CALIFORNIA.

PILE-DRIVING-FOLLOWER ATTACHMENT.

1,017,439.

Specification of Letters Patent.

Patented Feb. 13, 1912.

Application filed May 4, 1911. Serial No. 624,978.

To all whom it may concern:

Be it known that I, MATTHEW T. MCKENNA, a citizen of the United States, residing in the city and county of San Francisco and State of California, have invented new and useful Improvements in Pile-Driving-Follower Attachments, of which the following is a specification.

My invention relates to a mechanism whereby piles may be driven in deep water, and where the heads of said piles are to be submerged beneath the surface, and also to drive very short piles.

The invention consists in means for guiding the pile, and connecting the driving follower therewith so that the pile may be driven to any desired depth, and the mechanism subsequently detached.

The invention consists of the parts and the construction and combination of parts, as hereinafter more fully described and claimed, having reference to the accompanying drawings, in which—

Figure 1 is a vertical section showing the connection with the pile and follower. Fig. 2 is an enlarged section showing the pulleys and ropes for manipulating the connections between the sleeve and pile. Fig. 3 is a transverse section taken through $x-x$ of Fig. 2.

A represents the pile to be driven, and 2 is a follower which constitutes a part thereof, and which may be a pile or power transmitting member, and is designed to rest upon the head of the pile to be driven.

The cylinder 3 is bolted to the lower end of the follower and thereby constitutes a part of the latter, said cylinder extending downwardly and forming a casing within which the upper end of the pile, A, fits loosely.

4 is a shoe fitted on to the lower end of the follower 2 and secured in the cylinder and resting upon the head of the pile, and this shoe receives the shock of a driving hammer, and insures the whole length of the pile and follower being moved in unison, preventing also the tearing out of the bolts which secure the cylinder 3 to the follower.

Surrounding this inner cylinder 3 is a sleeve 5 of larger diameter leaving an annular space between the two; this space being maintained by longitudinal, lapping ribs 6 and 6' which are secured to the inner and outer sleeve respectively. The lower end of the

inner sleeve is provided with an upturned, conical flange, as shown at 3^a, the outer periphery of the upturned portion inclosing the lower end of the exterior cylinder 5, preventing mud from being forced up into the space between the two and having a working fit thereon.

7 are pawls having their lower ends fulcrumed to the interior of the outer sleeve as shown at 8. The pawls sustain the pile in the cylinder while being placed or moved about, the load of the pile jamming the pawls firmly in the wood. The inner ends of the pawls pass through slots 9 made in the inner casing and engage the pile, so that when the driving takes place, the outer casing will be moved down in unison with the movement of the pile. In order to engage these pawls with the pile A I have shown pulleys 10 journaled between the cylinder 3 and sleeve 5, and wire or other ropes 11 pass around these pulleys having their ends secured to the inner casing member 3. These ropes extend upwardly so that by a pull upon these ropes 11 the outer casing 5 will be lifted and the pawls forced into the wood of the pile.

The pile is driven by any usual well known means, and when sunk to the desired depth, which may be thirty or forty feet, or more under water, the apparatus is disengaged by means of ropes 12, which pass around another set of the pulleys 13. In this case the ropes have their ends attached to the outer cylinder 5, as shown at 14, and by the pull upon these ropes 12, the movement of the two casing sections is reversed; that is, the outer casing will be forced downward, carrying with it the pawls and withdrawing them from the slots 9, and from their engagement with the pile, leaving the points resting against the inner casing, after which the sleeves and follower may be drawn up and the pile left in position.

Having thus described my invention, what I claim and desire to secure by Letters Patent, is—

1. A pile driving apparatus, comprising a capping cylinder having a transverse plate adapted to rest upon a pile, and a section telescoping over said cylinder having pile engaging spurs.

2. An apparatus for driving piles in deep water comprising a follower adapted to rest upon a pile, means upon the follower for

sustaining the pile, and means adjustable in opposite directions upon the follower for supporting the sustaining means and causing the latter to engage with and disengage from the pile.

3. In a pile driving apparatus, the combination with a cylinder, adjustable over the top of the pile, of a sleeve concentric with the cylinder and movable relatively thereto, and provided with pile engaging devices adapted to sustain the pile in the cylinder.

4. A pile placing apparatus, including a cylinder adapted to embrace a pile, a sleeve movable over the cylinder, and dogs mount-

ed on the sleeve effecting to sustain the pile in the cylinder.

5. A pile placing apparatus, including a cylinder adapted to embrace a pile, a sleeve movable over the cylinder, dogs mounted on the sleeve effecting to sustain the pile in the cylinder, and means for disengaging the dogs from the pile.

In testimony whereof I have hereunto set my hand in the presence of two subscribers.

MATTHEW T. MCKENNA.
